(57) **CLAIM**

I claim the ornamental design for the rope clamp, as shown and described.

DESCRIPTION

FIG. 1 is a perspective view of a rope clamp;
 FIG. 2 is a front side view thereof;
 FIG. 3 is a back side view thereof;
 FIG. 4 is a top view thereof;
 FIG. 5 is a bottom view thereof;
 FIG. 6 is a left side view thereof; and,
 FIG. 7 is a right side view thereof.
